CUFF BUTTON OR SIMILAR ARTICLE

Otto Grun, New York, N. Y.

Application March 13, 1947, Serial No. 137,595

Term of patent 14 years

(Cl. D17—7)

To all whom it may concern:

Be it known that I, Otto Grun, a citizen of the United States of America, residing at the Borough of Manhattan, city, county, and State of New York, have invented a new, original, and ornamental Design for a Cuff Button or Similar Article, of which the following is a specification, reference being had to the accompanying drawing, forming a part hereof.

On the drawing,

Fig. 1 is a front elevational view of a cuff button or similar article, showing my new design;

Fig. 2 is a side view thereof;

Fig. 3 is a plan view of the same;

Fig. 4 is a rear elevational view; and

Fig. 5 is a front perspective view thereof.

The dominant features of my design reside in the parts shown in full lines, the back of the cuff button and connecting link shown in Figs.

2 and 3 being omitted in the other figures for convenience of illustration.

I claim:

The ornamental design for a cuff button or similar article substantially as shown and described.

OTTO GRUN.
